UNITED STATES PATENT OFFICE.

ARCHIBALD JONES, OF LANGELOTH, PENNSYLVANIA, ASSIGNOR TO METALLURGICAL COMPANY OF AMERICA, OF NEW YORK, N. Y., A CORPORATION OF NEW JERSEY.

ZINC RETORT-FURNACE.

1,282,847.

Specification of Letters Patent. Patented Oct. 29, 1918.

Application filed January 4, 1916. Serial No. 70,097.

To all whom it may concern:

Be it known that I, ARCHIBALD JONES, a citizen of the United States, residing in Langeloth, county of Washington, State of Pennsylvania, have invented certain new and useful Improvements in Zinc Retort-Furnaces; and I do hereby declare the following to be a full, clear, and exact description of the invention, such as will enable others skilled in the art to which it appertains to make and use the same.

My invention relates to an improved construction of zinc retort furnaces provided with a fire brick construction arranged above and incorporated with the furnace proper and forming a pre-heater or heat recuperator for pre-heating the air used for the combustion of the fuel in the furnace.

The invention will be further described in connection with the accompanying drawings, illustrating one embodiment thereof, in which,

Figure 1 shows, in vertical longitudinal section, a zinc retort furnace embodying the invention;

Fig. 2 is a horizontal sectional view, taken on the line 2—2 of Fig. 1;

Fig. 3 is a vertical transverse sectional view, taken on the line 3—3 of Fig. 2;

Fig. 4 is a side elevation of the furnace; and

Fig. 5 is a sectional view taken on the line 5—5 of Fig. 4.

The drawings show the upper portion of one section of a double furnace structure, the end walls of the furnace being indicated at 1, 1, and the upper rows of retorts, in the combustion chamber, being indicated at 2.

Above the furnace proper is a fire brick construction containing a series of flues for the products of combustion from the furnace, and for the air supply to the furnace, these flues being arranged to form a recuperator for pre-heating the air by means of the outgoing products of combustion. From the combustion chamber the products of combustion pass up the flue 5 into the horizontal flue 4, thence through the vertical connecting flue 4^a into the upper horizontal flue 6 and through the connection 7 to the stack 8.

Arranged above the flues 4 and 6 are air flues 10 and 9 communicating with each other by vertical flues 12. The upper air flue is provided with an air inlet 11.

As indicated in Figs. 3 and 4, the pillars

at the front of the furnace are made up of pillar blocks 13 and 20 which support the arch and the upper fire brick construction, and which also support the shelves 19 upon which the front ends of the retorts 2 rest. 60 The retorts are indicated in outline in Fig. 4.

It will be noted that the pillar blocks 13 extend out between the buckstaves 3, and that these extensions are hollow. It will also be noted that the pillar blocks 13 are 65 provided with passages 15 leading from the hollow extensions to the combustion chamber. The skewback 16 supported by the top pillar block, where this type of construction is used, is also made hollow. Arranged 70 thereabove, is the hollow block 17, the opening in which communicates with the passage in the skewback and, through a passage 18 in the furnace wall, with the lower air flue 10. The arrangement is such that the pre-heated air from the lower flue 10 enters the passages 18 and passes down through the opening 14 in the hollow pillar blocks and thence through the passages 15 to the combustion chamber. The hollow pillars 75 accordingly serve to conduct the pre-heated air from the recuperator arranged above the furnace proper to the combustion chamber. 80

It will be seen that the air flues and the exit flues for the products of combustion are 85 arranged in heat interchanging relation to each other so that the heat of the outgoing products of combustion is transmitted through the flue walls to the incoming air, and the air thus highly pre-heated. The 90 construction is moreover a unitary construction in which the fire brick construction forming the pre-heater is arranged on top of and incorporated with the furnace proper, and in which the flues for the pre-heated 95 gas from the pre-heater to the combustion chamber also form a part of the furnace construction. The arrangement of the flue structure for pre-heating the air above the retort containing combustion chamber is also 100 an advantageous arrangement because of the more direct passage of the products of combustion from the furnace to the stack and of the air through the flues and the hollow pillars to the combustion chamber. 105

It will further be noted that the hollow pillar blocks themselves are provided with vertical passages which form air flues, and that these pillar blocks are also provided with one or more ports leading from the 110

vertical passages to the combustion chamber of the furnace, so that the air can be supplied through the pillar and the hollow pillar blocks to the furnace chamber.

5. What I claim is:

1. A zinc retort furnace provided with hollow pillars having ports communicating with the retort-containing combustion chamber and supplying air thereto, said furnace 10 having exit flues for the passage of the outgoing products of combustion, and air-admission flues supplying air to the hollow pillars near the upper ends thereof and arranged in heat interchanging relation to the 15 exit flues, whereby the incoming air is pre-heated by the outgoing products of combustion; substantially as described.

2. A zinc retort furnace provided with hollow pillars having ports communicating 20 with the retort-containing combustion chamber and supplying air thereto, said furnace having exit flues for the passage of the outgoing products of combustion, and air-admission flues supplying air to the hollow 25 pillars near the upper ends thereof, said air-admission flues and exit flues being located above the combustion chamber and arranged in heat interchanging relation to each other, whereby the incoming air is pre-heated by 30 the outgoing products of combustion; substantially as described.

3. The combination in a zinc retort furnace having a furnace wall and coöperating buckstaves therefor, of a pillar incorporated 35 in said wall and forming a part thereof and built up of a plurality of pillar blocks, each of said pillar blocks having a vertical passage therethrough and a port leading from 40 said passage and communicating with the retort-containing chamber of the furnace, said pillar blocks being vertically disposed one above the other and so that the vertical passages therethrough are in substantial alinement; substantially as described.

4. A zinc retort furnace provided with hollow pillars built up of a plurality of hollow pillar blocks each of which has a vertical passage therethrough arranged to communicate with similar passages in the 50 other pillar blocks of the same pillar, each of said pillar blocks having a port leading from said vertical passage and communicating with the retort-containing combustion chamber of the furnace, exit flues for the 55 passage of the outgoing products of combustion of the furnace arranged above the retort-containing combustion chamber thereof.

and air admission flues arranged in heat interchanging relation with said exit flues and communicating with the vertical passages 60 in said hollow pillars near the upper ends thereof, whereby the incoming air is pre-heated by the outgoing products of combustion and directed downwardly through the vertical passages in said hollow pillars; 65 substantially as described.

5. The combination in a zinc retort furnace having a furnace wall and coöperating buckstaves therefor, of a pillar incorporated in said wall and forming a part thereof and 70 built up of a plurality of pillar blocks extending outwardly beyond the face of said wall, each of said pillar blocks having a vertical passage through the portion thereof extending beyond the face of said wall and 75 a port leading from said passage and communicating with the retort containing chamber of the furnace, said pillar blocks being vertically disposed one above the other and so that the vertical passages therethrough 80 are in substantial alinement; substantially as described.

6. The combination in a zinc retort furnace having a furnace wall and coöperating buckstaves therefor, of a plurality of spaced-apart pillars incorporated in said wall and forming a part thereof, each of said pillars being built up of a plurality of pillar blocks 85 vertically disposed one above the other, shelves resting upon and supported between 90 corresponding pillar blocks of said pillars, and retorts supported at one end by said shelves; substantially as described.

7. The combination in a zinc retort furnace having a furnace wall and coöperating buckstaves therefor of a pair of spaced-apart pillars incorporated in said wall and forming a part thereof, each of said pillars being built up of a plurality of pillar blocks 95 vertically disposed one above the other, each 100 of the pillar blocks of one of said pillars having a vertical passage therethrough arranged to communicate with similar passages in the other pillar blocks of the said pillar, each of said last mentioned pillar 105 blocks having a port leading from its vertical passage and communicating with the retort-containing chamber of the furnace, shelves resting upon and supported between 110 corresponding pillar blocks of said pair of pillars, and retorts supported at one end by said shelves; substantially as described.

In testimony whereof I affix my signature.
ARCHIBALD JONES.
